ABSTRACT

A detonation-reaction engine for attachment to a payload for propelling it at high velocities comprises a stage or stages, each having a sheet of explosive material, a sheet of material for restricting the propagation of the flame front, and a sheet of pressure-attenuating material encased in a lightweight, consumable structure. The attenuating material spreads out the pressure-time profile of the shock wave generated by the detonating explosive, and this somewhat reduces the intensity of the shock wave before it reaches the payload or the next engine stage. In this manner, the payload can be subjected to a series of successive detonation impulses from the successive stages occurring microseconds from each other in time, thereby adding successive increments of velocity to the payload.

CONSUMABLE DETONATION REACTION ENGINE AND SYSTEM

This invention relates to reaction engines, and more particularly to such engines of the detonation-reaction type.

Reaction motors or engines comprising a pressure chamber wherein fuel is burned and an exhaust nozzle through which combustion products of the burned fuel are exhausted from the chamber to produce thrust are well known. It is also well known that explosives can be used to propel objects over a wide velocity range, depending upon the method of controlling the energy transfer to the object and upon the nature of the explosive. It has also been known that detonated explosives can accomplish such a propelling operation without the need of a pressure vessel or exhaust nozzle.

The transfer of energy from a detonating explosive to an object being propelled occurs when the detonation wave interacts with the interface of the explosive and the object to send a compression or shock shock into the object. Pressures attained behind such shock waves are extremely high; for example, far beyond the ultimate strength of steel, which of course can involve the risk of damage to the object being propelled.

Objects of the present invention are to effect propulsion of an object or payload by explosive detonation in such a manner as to avoid damage or destruction to the payload, or of the propulsion engine itself before having performed its function, and to obtain exceptionally high velocities.

In carrying out the invention, use is made of an engine stage behind the projectile or payload comprising a sheet-like layer of explosive and a shock-wave-attenuating means between the explosive layer and the payload or the next stage of the engine, as the case may be. According to a preferred feature of the invention, the engine is a plural or multi-stage engine; hence, there can be achieved a staged rocket-like reaction engine using multiple energy pulses from detonating explosives, but requiring no pressure vessel nor exhaust nozzle.

The control, that is, the timing of the detonations, is important to the successful practice of the invention. Such control is obtained by preventing the detonation shock waves from one stage from causing detonation of another stage, together with means for initiating the detonator for the next unburned stage.

In order to achieve such detonating propulsion, particularly staged detonation propulsion, the reaction engine is comprised of components which filter the flame front resulting from a detonation, attenuate the shock wave to prevent uncontrolled or sympathetic detonation of the unburned explosive, and initiate the detonator for successive layers of explosive at regulated time intervals. This is carried out by use of filters, attenuators, and detonator igniters associated with the stages.

Another feature of the detonation-reaction engines according to this invention resides in their consumability. This results in reduction of the weight of the engine as it is consumed, allowing a higher velocity increment to be applied to the payload.

The foregoing and other features of the invention will be better understood from the following detailed description and the accompanying drawings of which:

FIG. 1 is a longitudinal cross-section view of a payload associated with a single-stage detonation-reaction engine according to this invention;

FIG. 2 is an end view of the payload and system of FIG. 1 viewed from the payload end;

FIG. 3 is a cross-section view of a device, similar to that of FIG. 1, provided with a two-stage detonation-reaction engine according to this invention;

FIG. 4 illustrates a wrapping which may be applied around a device according to this invention;

FIG. 5 is a longitudinal cutaway view of a payload associated with a four-stage detonation-reaction engine according to this invention;

FIG. 6 is an end view of the system of FIG. 5 viewed from the propulsion end; and

FIG. 7 is an enlarged view of the encircled section of FIG. 5, more clearly illustrating the relationship of the 15 components of the four-stage detonation-reaction engine with a wrapping applied thereon according to this invention.

In FIG. 1 there is shown an object or payload 10 to be propelled by a detonation reaction and is represented in the form of a solid cylinder of material; for example, a length of steel rod. The payload 10 or steel rod is illustrated as being circular when viewed from the end as in FIG. 2 which shows the payload 10 in a plane perpendicular to the longitudinal axis 11 of the rod. It 20 should be understood that the payload or projectile may take some other form as may be convenient or desired. At one end of the rod or payload there is placed a detonation-reaction engine 12 comprising a circular disc or sheet 13 of explosive of substantially the same 25 diameter as that of the end of payload to which it is attached. A detonator 14 aligned with the longitudinal axis 11 of the payload has its forward end attached to the rear side of the explosive 13, the detonator being detonable in any well known manner, such as an electrical means embodying the wires 15 which lead to a source of electric current and which can be turned on by means of a suitable switch (not shown) to initiate detonation. The front face of the explosive disc 13 is 30 covered by a sheet of suitable material to act as a filter 35 for the flame front generated. The sheet 16 acts as a filter in that it permits the transmission of a shock wave generated by the explosion of the explosive disc 13; however, it impedes the propagation of the flame front. Between the front face of the sheet 16 and the rear face 40 of the payload 10 there is placed a circular disc 18 of a slightly compressible material which acts as a detonation-wave-attenuator, the forward face of which is in contact with the rear circular face of the payload 10.

The components of the detonation-reaction engine 45 and the payload can be held together in any suitable manner; for example, by use of adhesive such as an epoxy resin at the interfaces of each of the components 13, 14, 16, 18, and 10; or alternatively, by use of an external wrapper, such as a resinous sheet (not shown) 50 around the cylindrical circumference of the composite structure.

The sheet 13 may comprise practically any detonating explosive capable of being formed into or held 55 within a sheet or disc, for example, PETN (pentaerythritol tetrinitrate) HMX (1,3,5,7-tetranitro-1,3,5,7-tetrazacyclooctane), dynamite, nitrocellulose, nitroglycerin, or the like; or the mixtures of explosives or explosive gases or liquids capable of being encapsulated 60 within the sheet structure or a nuclear-type explosive.

The filtering sheet 16 can be of a convenient material, including solid metals or plastics, or the like. For example, aluminum foil capable of blocking or resisting the

propagation of a flame front. The detonation-wave-attenuating disc 18 may be of a suitable material providing an impedance to the propagation of the detonation wave which substantially mismatches the impedance of components 13 and 16, thereby augmenting the attenuation. Suitable materials for the attenuating component 18 include those which contain air spaces or gaps; for example, polyurethane foam or the like formed from such materials as rubber or plastic. Such attenuating members tend to compress under the impact of the shock wave or detonation wave, thereby helping to produce a more planar and subdued pulse at the payload side of the attenuating disc.

To operate the device, it may be placed on or in a suitable launcher in a manner similar to the launching of a rocket or alternatively within a gun barrel or the like which may be open at both ends. Firing of the detonator 14 detonates the explosive sheet or disc 13 which sends a detonation wave forwardly toward the projectile through the sheet 16 and through the attenuating disc 18 which reduces the harmful effects of the detonation on the material of the projectile. The force of the detonation wave nevertheless sends the projectile forwardly at high velocity.

The effectiveness of propulsion by use of a detonation-reaction engine is greatly enhanced by use of multiple detonation stages in the engine. In this manner, only small velocity increments are imparted to the payload with a reduction in stress on the structure and payload, and with an increase in efficiency of explosive utilization. FIG. 3 illustrates the use of a two-stage detonation reaction engine. In FIG. 3, the payload 10 is shown similar to the same numbered payload in FIG. 1. The first engine stage is somewhat similar to the engine of FIG. 1 in that it comprises the explosive disc 13 detonable by a detonator 14 and the detonation-wave-filtering sheet 16. Instead of a disc-shaped member such as 18 of FIG. 1, there is provided a member 19 which may be of the same material as described for component 18 of FIG. 1 but formed with a rearwardly protruding cylindrical portion 20 which abuts the sheet 16 and around which there is placed an annular member 21 of a wave-attenuating material, such as described for member 18 of FIG. 1, and having the same outside diameter as the payload and other components of the engine.

The second stage of the engine shown in FIG. 3 is similar to the first stage of the engine in FIG. 1 in that it comprises the components 13, 16, and 18 behind the payload constructed and arranged similar to the same numbered components in FIG. 1. A detonator 22 placed at the rear side of the explosive 13 of this second stage serves to detonate this explosive. The detonator 22 for the second stage or successive stages of the engine is a type providing a predetermined time delay, as for example, a solid propellant grain-to-lead azide delay train, mild detonating fuses, percussion sensitive detonators, or electric field generators.

In operation of the device of FIG. 3, detonation of the detonator 14 detonates the first stage explosive 13 from which the detonation wave travels forwardly through the filter sheet 16 and the attenuator 18, arriving at the detonator 22 wherein the detonator 22 is initiated and after a very short interval of time the explosive 13 of the second stage is detonated.

FIG. 4 illustrates the use of a circumferential wrapping 23 around the components of the device. Although it is shown with particular reference to the sin-

gle stage structure of FIG. 1, it will be recognized that it applies equally to multi-stage structures. The wrapping 23 may be of any suitable material such as fiber glass or plastic material or the like, which may, if desired, be applied to the circumference by adhesive. Alternatively, the material 23 could be a shell such as a metallic shell, for example, aluminum. Use of such an exterior wrapping can, if desired, permit dispensing with use of adhesive between engine components.

Reference is made to FIG. 5 wherein there is shown a four-stage detonation-reaction engine. The payload 10 is shown similar to the same-numbered payload in FIGS. 1 and 3. The first engine stage is somewhat similar to the engine of FIG. 1 in that it comprises the explosive disc 13 detonable by the detonator 14 and the detonation wave filter sheet 16. The detonator 14 is shown housed in a light-weight plastic foam structure 24. Instead of a sheet of detonation-wave-attenuating material 18, as shown in FIG. 1, there is provided a honeycomb structure 17 in which the detonation-attenuating material 18 is dispersed. The honeycomb structure 17 is a light-weight consumable honeycomb structure and provides additional structural strength in addition to helping maintain control of the system alignment. The detonator 22 shown in FIG. 5 may be the same as the detonator 22 shown in FIG. 3.

Reference is made to FIG. 6 wherein there is illustrated an end-view of the system as viewed from the propulsion end. The detonator 14 is shown in its housing of a light-weight plastic foam structure 24. In the cutaway portion of FIG. 6 there is shown the honeycomb structure 17 in which the detonation-wave-attenuating material is dispersed.

FIG. 7 is an enlarged view of the encircled area of FIG. 5. This FIG. 7 illustrates the sheet of explosive 13 and the sheet of filter material 16 being disposed between sections of honeycomb structure 17 in which detonation-wave-attenuating material 18 is dispersed. FIG. 7 also shows the use of the circumferential wrapping 23 around the components of the engine.

In operation of the device of FIG. 5, detonation of the detonator 14 detonates the first stage explosive 13 from which the detonation wave travels forwardly through the filter sheet 16 and the attenuator material 18 arriving at the detonator 22. The detonator 22 is initiated and after a very short interval of time the explosive 13 of the second stage is detonated. This procedure is repeated as each stage is detonated in succession. In this manner, only small velocity increments are imparted to the payload 10 with a reduction in stress on the structure and the payload, and with an increase in efficiency of explosive utilization.

It will be recognized that any number of stages may be used in the engine and it will be ordinarily desirable to provide many more stages than the two or four illustrated in the drawings. The first and subsequent stages of an engine having more than four stages would be similar to the device illustrated in FIG. 5. It becomes apparent to those versed in the art that the last stage of a multiple-stage engine may be modified in that the detonator for the last stage would not require the timing control mechanism as necessary in the intermediate stages.

In the operation of a unit having a multi-stage engine, the detonations of the successive stages will occur in rapid succession and the detonation action will appear continuous since there will be only a matter of micro-

seconds between successive detonations. Each successive detonation will give the device an added increment of forward velocity, resulting in an extremely high end-velocity for the payload. The detonation-reaction engine itself is self-consuming while the detonations are occurring; hence there is a continuous lightening up of the device as the detonations progress, resulting in less and less mass to be propelled, which is advantageous in obtaining maximum velocity for the payload. From the foregoing description, it becomes apparent to those with skill in the art that the detonation-reaction engine herein described possesses the inherent capability of permitting a shutdown and restart being designed into it should a specific application require this feature.

The payload can take any of many useful forms, such as, but not limited to, structural piles, artillery shells, rockets, including sounding rockets and missiles.

The embodiments shown in the drawings and described in the description are given by way of example and it will be apparent to those skilled in the art that modifications and variations may be made without departing from the spirit and scope of the appended claims.

What is claimed is:

1. A consumable detonation-reaction engine adapted to be mounted on the end of a payload, said engine comprising a plurality of stages arranged in tandem along an axis extending in the direction of forward impulse, each said stage comprising:

an explosive member;

means adapted to said explosive member for detonating the explosive;

a flame-front-filtering means in front of the explosive member for restricting propagation of the flame front through it in the forward direction; and

a shock-wave-attenuating means in front of the filtering means and comprising a structure of air impregnated foam material having a predetermined compressibility substantially mismatching the compressibility of the explosive member and the flame front filtering means for reducing the impulse of the shock wave passing forwardly through it and more evenly planarly distributing said impulse.

2. An engine in accordance with claim 1 wherein the means for detonating said explosive member of each stage sequentially from the initial stage is positioned at its respective stage to receive the impulse of the detonation wave resulting from the detonation of the adjacent rearward stage as said wave passes forwardly through the attenuator of said adjacent rearward stage.

3. An engine according to claim 2 wherein the detonating means for each stage subsequent to the initial stage includes a delay train which is initiated by the impulse of the detonation wave resulting from the explosion of the adjacent rearward stage.

4. An engine according to claim 1 wherein the detonating means is further adapted so that the detonation from the explosive of each stage excepting the forward-most stage initiates the detonation of the explosive of the adjacent forward stage and the impulse from the detonation of each stage is transmitted forward and is applied against the rearward face of the payload, the detonations occurring in rapid succession while the payload is being propelled forwardly and while the stages of the engine are being consumed in succession.

5. An engine in accordance with claim 1 wherein said explosive member is in the form of a sheet of explosive

and said filtering means is in the form of a layer of material covering the forward surface of the explosive sheet and the attenuating means comprises a shock-wave-attenuating material covering the forward surface of the filter, and the payload is mounted to the engine to abut the forward surface of the attenuating means of the most forward stage.

6. An engine in accordance with claim 1 wherein said filtering means is a sheet of solid material having means to permit restrictive passage of the flame front resulting from detonation of the explosive.

7. An engine in accordance with claim 1 wherein means is provided holding the explosive member, the filter means, and the attenuator means in contact with each other.

8. An engine in accordance with claim 1 wherein the payload and stages of the engine are cylindrical.

9. An engine in accordance with claim 1 wherein said shock-wave-attenuating means is encased in a light-weight, consumable honeycomb structure.

10. A consumable detonation-reaction engine having at least one stage comprising: a sheet of explosive material; a filter of flame-resistant material covering the forward surface of the explosive sheet; and a layer of shock-wave-attenuating material covering the forward surface of the filter, said shock-wave-attenuating material comprising air-impregnated foam material, the compressibility of which is substantially greater than the compressibility of the explosive material and the filter whereby the flame front from the detonation of the explosive layer is impeded by said filter but the shock wave thereof passes through said filter, said shock wave being attenuated by the shock-wave-attenuating material to reduce the peak impulse resulting from the detonation of said stage.

11. An engine in accordance with claim 10 wherein said filter layer includes means for permitting restricted passage of the flame front therethrough.

12. An engine in accordance with claim 11 wherein said shock-wave-attenuating material is encased in a light-weight consumable honeycomb structure.

13. A consumable detonation-reaction engine adapted to be mounted on the end of a payload, said engine comprising a plurality of stages arranged in tandem along an axis extending in the direction of forward impulse, each said stage comprising an explosive member, a flame-front filtering means in front of the explosive member for restricting propagation of the flame front in the forward direction, a shock-wave-attenuating means in front of the filtering means and comprising a foam material encased in a light-weight consumable honeycomb structure, the compressibility of said foam material being substantially greater than the compressibility of the explosive member and the filtering means for reducing the impulse of the shock wave passing forwardly through it; means adapted to the explosive member of the rear-most stage for detonating the explosive of said rear-most stage; and means for detonating the explosive member of each other stage, said later detonating means being activated by the impulse of the detonation wave resulting from the explosion of the adjacent rearward stage so that the

14. An engine according to claim 1 wherein said compressible material comprises air-impregnated foam encapsulated in a light-weight consumable honeycomb structure.
